POLE GAINING MACHINE

Robert L. Efurd, Jr., and Euland A. Efurd,
Shreveport, La.

Application January 14, 1948, Serial No. 2,255

2 Claims. (Cl. 144—133)

1

Our invention relates to pole framing machines generally, but more in particular to a type of pole framer arranged and designed for the complete framing of poles to meet utility, telephone and Rural Electrification Administration requirements. Since most electrification and telephone projects are carried out in rural communities, or in areas removed from great supply centers, it is highly advantageous to have a complete pole frame that may be carried from one location to another and may be set up to operate with a minimum of effort and to frame the pole in the shortest time possible.

Throughout the following description the phrase "roofing the pole" is intended to mean the sawing of the top end of the pole, whether at right angles to the length of the pole or at an obtuse angle thereto. The phrase "butting the pole" shall mean the sawing of the butt end of the pole at any required angle. The word "gain" refers to the forming of a flat surface on the pole—the operation being similar to "spotfacing" or "slab milling" in the metal trades.

An object of our invention is to provide a pole framing machine that will prepare the pole with the necessary cross cuts and slab gains as well as drill the proper holes for the cross arms and braces.

It is another object of our invention to provide a pole framing machine arranged to roof and butt the pole, the gain cutter element and the drilling mechanism being operated from the same source of power.

Another object of our invention is to provide a pole framing machine that is portable, thus allowing it to be moved from one location to another where the poles are more accessible.

Further objects and advantages will appear in the following detailed description when viewed together with the accompanying drawings in which:

Figure 1 is a side elevational view of a device embodying our invention in a pole framing machine showing the butt sawing mechanism and the travelling gain buggy in an operative position to feed a pole under the cutter element.

Figure 2 is a plan view of the machine, the butt sawing machine and the gain buggy being removed.

Figure 3 is a broken plan view of the cutter element, the drill and the driving means therefor.

Figure 4 is a broken view showing the guide rollers that guide the pole into position under the cutter element.

2

Figure 5 is a side view of the main truck which carries the cutter element and driving means.

Figure 6 is a broken vertical sectional view through the drill mechanism.

Figure 7 is a broken perspective of a pole assembly after the pole has been operated on by the pole framer.

Figure 8 is a broken plan view of the roofing saw arrangement.

Figure 9 is a broken side view thereof.

Figure 10 is a broken side view of the main truck showing a modified position of the driving means.

Figure 11 shows another modification of the driving means and a modified cutter element.

Figure 12 is a vertical sectional view through the modified cutter element shown in Fig. 11.

Referring now to the drawings, numeral 10 designates the main frame which is made up of rigid uprights 11 and cross members 12, suitably braced by gusset plates 13. One of the cross members of the frame 10 carries a horizontally mounted roller 14, the center shaft of which is journalled in the side framing members. Another of the cross members 12 carries a pair of angularly disposed rollers 15, arranged to position the pole with respect to the cutter element of the machine, as shown in Figures 1 and 4.

The frame 10 is also provided with a pair of rails 16 whereby the truck frame 17 may be moved along and fed into the pole 18. As shown in Figure 3, the frame also supports an operator's platform 19 and a calibrated scale 20 placed along one of the rails 16. The truck frame 17 carries a pointer 21 which is arranged to move just above the scale 20. Thus an operator, standing on the platform 19, may see just how far to advance the machine along a pole during a slab gaining operation.

In Figures 3 and 5 the truck frame 17 is mounted on suitable wheels 22 to allow it to be pushed by an operator along the guide rails 16. It also carries the cutter element designated generally by the numeral 23 together with the drill mechanism 24. The driving motor 25 is mounted on a cross arm 26 which is, in turn, pivotally mounted to the side walls of the truck frame 17, the axis of mounting being on the same plane as the shaft of the driving motor 25. Thus when the cutter 23 or the drill 24 is being used, the movement of the cross arm 26 will have no effect on the driving pulleys or connecting belts.

On the inner end of the cross arm 26 is the cutter element 27 mounted horizontally on a shaft which is rotatably mounted in end plates

28 pivotally connected to the cross arm 26 by a pivot pin 30. These end plates 28 also carry a roller 29 rotatably mounted in the end plates 28. On the upper end of the end plates 28 is a pivotally connected adjusting mechanism 31 the opposite end of which is pivotally connected to the truck frame 17. The adjusting mechanism consists of a pair of oppositely threaded studs 32, joined by a convenient adjusting wheel 33. When an operator wishes to lower the cutter element 27 to make a deeper cut into the pole 18, he turns the wheel 33 in a direction according to the threads of the studs 32. This adjustment will in turn pivot the end plates 28 and raise or lower the roller 29, accordingly, the roller 29 acting as a depth stop at any depth setting of the adjusting mechanism 31. We have also provided an upwardly extending handle 34 affixed to the cross arm 26 whereby an operator might hold the roller 29 down against the pole 18.

On the opposite end of the cross arm 26, there are weights 35 which may be adjusted along the cross arm 26 to counterbalance the weight of the mechanism on the opposite end. It is preferred that the weights 35 be so set as to raise the cutter 27 away from the cutting position on the pole 18 when the operator removes his hand from the handle 34. Thus the cutter will be assured of remaining clear of an incoming pole until the operator forces it into its cutting position again by applying weight on the handle 34.

Mounted on a framework 36 at the rear of the truck frame 17 is the drill assembly mechanism 24. The assembly consists of a housing 37 bored to fit a slidable sleeve 38. The main shaft 39 extends up into the sleeve 38 and is arranged to be rotated by a pair of bevel gears 40. The driving gear is mounted on a shaft which is rotated by the driven pulley 41 connected to the motor 25 by belts. The upper end of the sleeve 38 is provided with a handle 42 arranged to be guided by a slot 43 in the housing 37. The upper end of the slot 43 is provided with a notch 44 so that the handle might be locked in the upper position.

Mounted beneath the rear end of the main frame 10 is the roofing saw mechanism as shown by Figures 8 and 9. The saw proper 45 is mounted on a rotatable shaft 46 suitably journaled in bearings 47 mounted on a beam bar 48. The beam bar 48 is supported by uprights 49, the lower ends of which are mounted on a swivel base 50. On the outer end of the beam bar 48 is an extending handle 51, whereby an operator may turn the saw to any degree of angularity with respect to the horizontally positioned pole, such degree of angularity being noted by the pointer 52 and the calibrated quadrant 53. The saw 45 is rotated by a driving motor 54 mounted beneath the beam bar 48 and connected to suitable pulleys and belts.

In Figure 1 the travelling buggy 55 and the butt sawing device 56 are of prior art construction and form no part of the present invention. Both the buggy 55 and the butt sawing mechanism 56 are mounted on wheels and adapted to be moved along the guide rails 69. These guide rails 69 will, of course, be placed in proper alignment with the main frame 10, and may even be connected thereto. The buggy 55 is provided with a pair of rotatable discs 57 arranged in a manner similar to the rollers 15 on the main frame 10. The discs are pivotally mounted on the framework and may be tilted to one side by the handle 58 to allow the pole to be rolled off 75

its position on the frame 10. The buggy 55 also supports the pole while the butt is being sawed by the butt sawing mechanism 56.

A brief description of the operation of our device will follow. Let us assume that a number of poles 18 must be prepared for a pole assembly as shown in Figure 7 with the butt 59 cut square with the pole and the top 60 at a 45 degree angle, and a short slab 61 cut for a cross arm assembly 10 62. It will also be necessary to drill the cross arm bolt hole 63. The machine is best operated with three workmen, one standing on the platform 19 to operate the cutter and drill mechanisms and the other two handling the butt saw 15 56 and the buggy 55.

The pole 18 is placed on the frame 10 and dropped into the forward guide rollers 15, the rear end of the pole being placed in the centralizing rollers 57 of the buggy 55. An operator then 20 moves the buggy to where the butt end of the pole may be squared by the butt saw 56. At the same time the forward operator moves the truck frame along the rails 16 to a cutting position. After noting his starting point on the calibrated 25 scale 20, he lowers the cutter mechanism 23 into place by forcing down the handle 34. Should the cut be not deep enough or too deep, the operator makes the necessary adjustments by turning the adjusting wheel 33. When the pointer 21 reaches the desired marking on the scale 20, the operator releases the handle 34. The weights 35 30 will automatically lift the cutter mechanism 23 away from the pole, and the operator will move the truck back to its starting position. It is required that the pole be topped with one 45 degree cut. Having previously set the topping saw 35 at this setting according to the calibrated quadrant 53, the operator simply has to press downwardly on the handle 51 which pivotally raises the saw 45 to make the necessary cut. Should 40 it be required that two angular cuts be made, the operator will pivot the saw in a horizontal direction and make the cuts accordingly. The saw proper 45 and its related bearing arrangement are so positioned on the beam bar 48 that 45 their combined weight will overcome the weight of the motor 54, and thus automatically lower the saw out of its cutting position when the weight has been removed from the handle 51.

Using either the buggy 55 or the truck frame 17, the operator makes ready to drill the cross arm hole 63. By lifting the handle 42 from its locked position in the notch 44, he lowers the shaft 39, allowing the weight of the shaft 55 to force the drill bit 64 to drill the hole. After the drilling the operator raises the shaft and locks the handle into the notch 44, and the pole is ready to be removed from the machine. We have found in actual practice that the above 60 described operations may be performed in one minute's time. This is highly advantageous to pole framing operations since most electrification projects are required to be completed with the most speed possible. To remove the pole 65 from the machine, the buggy 55 is pushed backward to where the forward end of the pole will be removed from the guide rollers 15, allowing it to drop on the horizontal roller 14. The rollers 57 of the buggy are then tipped to one side by the handle 58 and the pole is rolled onto the bed of the waiting vehicle.

In Figure 10 is shown a slight modification of the travelling truck 17. In this instance the motor 25 is mounted above the pivot point P 70 of the cross arm 26. The rotatable shaft 65

has suitable pulleys for driving the cutter mechanism 23 and the drill assembly 24. In this manner the cutter mechanism 23 may still be moved in the directions of the arrows without tightening or loosening the connected driving belts or interfering with the drill assembly 24.

Figure 11 shows the motor 25 mounted in a vertical position between the side frames of the truck 17 and arranged to rotate the drill assembly 24 by a direct connection of belts and pulleys, thus dispensing with the set of gears as shown in Figure 6. Figure 11 also shows a modified cutter assembly 66, a section of which is illustrated in Figure 12. In this instance the cutter proper 67 is made to rotate horizontally similar to any prior art drill press assembly. The modified cutter assembly is fixed stationary to the truck upon a bracket 70 and may be set to any desired depth of cut by adjusting the convenient handles 68.

While we have given a brief description of the construction and operation of our invention both in the preferred and modified form, it will be readily apparent that various changes in this construction may be made without departing from its spirit and scope as defined by the appended claims. The delivery and removal of the poles from the machine may be greatly facilitated by the use of a conveyor system similar to that used in saw mill operations. It will also be remembered that the pole may be reversed in the machine so the toppling operation and holes may be placed in the butt of the pole. The pole may also be pushed all the way through the machine in order to make a cut on the entire length of the pole.

Throughout the specification and claims we use the term "pole" as synonymous with "post" and desire that our invention be construed as applicable to all sizes of posts or poles.

We claim:

1. In a pole machine including a longitudinal framework, a pair of spaced rails extending from one end of said framework at a position adjacent to the bottom of said framework and a second pair of spaced rails positioned longitudinally on the top side of said framework and parallel to said first mentioned set of rails, the combination of a wheeled buggy mounted on said first mentioned rails, said buggy being adapted to support a pole or the like in transit over said framework, a pair of oppositely inclined rollers mounted on said framework adapted to embrace and support an end portion of a pole or the like positioned on said buggy, a wheel truck mounted on said second mentioned pair of rails adapted for movement on the same, a beam bar pivotally mounted at a medial portion of its length on a transverse axle rigidly

joined into said truck, a cutter means mounted on the forward end of said beam bar, manual means for engaging said cutter means with a pole or the like supported by said buggy and said oppositely inclined rollers, and an adjustable weight means mounted on the rear end of said beam bar, said weight means being adapted to be moved longitudinally of said beam bar to balance said beam bar or overbalance the same about its axis of rotation.

2. A pole machine comprising a framework, a pair of rails positioned longitudinally along said framework, a wheeled truck adapted for movement along said rails, a beam bar pivotally mounted between the side walls of said truck, a pair of swivelly mounted spaced side plates on one end of said beam bar, a horizontally disposed cutter element rotatably mounted between said side plates, a roller rotatably mounted between said side plates forwardly of said cutter element, means for lowering said beam bar to a position where said roller will tangentially engage a pole placed beneath the same, means for raising or lowering said cutter element with respect to said roller to gage the depth of a cut made by said cutter element on the pole with which said roller is engaged consisting in a threaded rod pivotally mounted to said side plates, said threaded rod being connected to an oppositely threaded rod pivotally connected to said truck, the oppositely threaded ends of each of said rods being engaged by a correspondingly oppositely threaded sleeve adapted to pivot said side plates upon being turned in a clockwise or counterclockwise direction.
